UNITED STATES PATENT OFFICE.

ELVA L. BELL AND ORLANDO M. BEEBE, OF SPOKANE, WASHINGTON.

ROOFING STRIP.

Application filed September 6, 1927. Serial No. 217,772.

This invention relates to roofing strips for buildings, and more particularly such a strip having a scalloped edge and having a collapsible fastener applied thereto.

5 The object of the invention is to provide roofing strips which can be applied to the roof in different relative positions to produce a wide range of ornamental effects. Another object is to provide such a strip with 10 an attached fastener in such a manner that the strip with the fastener may be rolled for the purposes of transportation and handling by the roofer. A further object is the provision in a strip of this kind of indicia to assist 15 the roofer to lay it quickly and accurately, and in a wide range of designs. A still further object is the production of a fastener which will avoid liability of moisture reaching the roof proper through the holes in the 20 strip produced by the securing elements.

Other objects and advantages of the invention will hereinafter appear in the following description and the novel features thereof will be particularly pointed out in 25 the appended claims.

Like letters of reference indicate like parts throughout the several figures of the drawings, in which

Figure 1 is a plan of a portion of a roof 30 having a number of the strips applied thereto,

Figure 2 is a plan of a portion of a piece 35 of roofing material from which two strips may be cut and showing a method of providing the strips with indicia for proper alignment of the strips upon a roof.

Figure 3 is an end view of a rolled package formed by the strip with fasteners attached.

Figure 4 is a longitudinal section through a fastener attached to the strip, and

40 Figure 5 is a perspective of the fastener as applied with the strip shown in dotted lines.

The invention has been shown as embodied 45 in a strip of roofing fabric or similar material, such as is commonly employed for composition shingles for roofs, which may be graveled if desired, and is designed to be made in lengths equal to or greater than the width of the roof to be covered. Such strips 50 may be rolled into bundles and are placed on the roof by unrolling and securing them to the roof in overlapped relationship so that a portion of one strip protects the edge of the next strip below. The attached fasteners 55 are employed to secure the overlapped edge

of an adjacent strip as well as the strip to which they are secured.

In Figure 2 is shown a portion of a length of roofing fabric or material, such as is commonly used in the manufacture of composition shingles for roofs. This may be graveled if desired, and may be of any desired color. By cutting this strip longitudinally 60 on the line A—A, two strips 10 and 10' are formed, which are duplicates and a description of one will be sufficient.

The strip 10 has one straight edge 11 and a scalloped edge 12, defining lobes 13 and concavities 14. The lobes are regular in size and shape. It will be appreciated that at the 70 point where a lobe is formed in strip 10, a concavity is formed in the scalloped edge of the strip 10', and where a concavity is formed in the strip 10, a lobe will be formed in the strip 10'. By the term "scalloped edge" is 75 meant any edge having an irregular form, and by the term "lobes" it is intended to include any projections in said scalloped edge which occur regularly therein.

In order that the strips may be accurately 80 and quickly positioned upon the roof there is provided along the line A—A marks or indicia 15 at the centers of the lobes and at the centers of the concavities, such a mark being simply a scoring of the material or the 85 equivalent thereof. These marks or indicia are used in securing the proper alignment of the strips with relation to each other, to secure the desired ornamental effect by providing the roofer with a point on the laid 90 strip to measure from.

To each lobe is secured, at a point slightly removed from the edge of the strip, a collapsible fastener 16. Both the location of the fastener on the strip and its construction 95 are productive of results in a roofing strip of this type. When the strip is applied to the roof, its scalloped edge overlaps and protects the straight edge of an adjacent strip. In securing the lobe portions of the strip to 100 the roof, the overlapped edge of the adjacent strip is secured.

The fastener shown is made from a single piece of sheet metal of substantially diamond shape. The ends of the blank form attaching prongs 17 and 18, while from the center of the blank is struck down a securing prong 19. This securing prong is struck out to lie in a plane slightly below the plane of the fastener body, as shown in Figure 4, so that 110

it may be bent into the position shown in dotted lines in Figure 5 by the roofer at the time the strip is applied to the roof.

The fastener is attached to the strip by 5 passing the prongs 17 and 18 through the same from the under side and clenching the points of these prongs upon the face of the strip. Only the points of the prongs are visible and the apertures made in the strip 10 are relatively small. There is little chance of moisture collecting upon the roof finding its way to the under side of the strip.

The securing prong 19 is formed at a point intermediate the attaching prongs, and the 15 aperture made by it through the overlapped strip is entirely out of alignment with those made by the prongs 17 and 18 in the strip above. Any moisture which might find its way through the superposed strip would not 20 creep to the aperture formed by the prong 19. By applying the strip in this manner, the fastener is protected from the action of the weather, and is practically hidden from view, and the roof is protected from seeping water.

25 By securing the fastener to the strip as shown in Figures 4 and 5, where the securing prong is collapsed, and attaching it to the lower portion of the lobes 13, the strip may be rolled for transportation and handling. 30 The added thickness at the lobes due to the presence of the fasteners is compensated for in the decrease of strip material at that end of the roll due to the concavities in the strip.

It will be appreciated that a rolled roof 35 strip made in lengths to cover the whole width of the roof eliminates seams and particularly side laps. In laying the roof, the strips may be overlapped as shown in Figure

1, where the lobe of one strip registers with the concavity in the adjacent strip. The 40 marks 15 in that event register. But it will be appreciated that the strips may be positioned on the roof in a wide range of relationships, resulting in a variety of produced designs, and these may be augmented by the 45 making of adjacent strips of different colors.

What is claimed is:

1. As an element of a roof made up of plurality of strips of composition material applied in overlapped relationship, a strip 50 of flexible material having one edge scalloped, and fasteners in the lobe portions of said edge adapted to hold said lobe portions flat against the underlying strip and to pass through said underlying strip into the roof 55 to secure both strips in place.

2. The combination of claim 1, wherein the lobes and concavities of the scalloped edge are provided with matching indicia.

3. As an article of manufacture, a roof- 60 ing strip in roll form comprising a length of flexible roofing material having one of its edges straight and the other edge scalloped, and fasteners secured in the lobes of said 65 scalloped edge designed to hold said lobes flat against an underlying strip and to pierce said underlying strip and the roof.

4. The combination of claim 3 in which the fastener comprises lobe-piercing and roof- 70 piercing prongs which are out of vertical alignment.

In testimony whereof we affix our signatures.

ELVA L. BELL.
ORLANDO M. BEEBE.
